(57) **ABSTRACT**

A scroll compressor includes a compression mechanism with a compression chamber. The compression chamber is a combination of a fixed scroll and an orbiting scroll, and is to compress working gas. The fixed scroll includes a main port, and a plurality of sub-ports. The main port is a port through which the working gas compressed in the compression chamber is to be discharged. The sub-ports are ports through which the working gas over-compressed in the compression chamber is to be discharged. The scroll compressor includes a rotary shaft, and a silencing chamber. The rotary shaft drives the compression mechanism. The silencing chamber is disposed downstream of the main port with respect to the flow of the working gas. The silencing chamber includes a discharge hole, an expansion part, and a plurality of chamber sub-ports. The discharge hole is a hole through which the working gas is to be discharged.

**CROSS-REFERENCE TO RELATED
APPLICATION**

This application is based on PCT filing PCT/JP2021/021708, filed Jun. 8, 2021, the entire contents of which are incorporated herein by reference.

TECHNICAL FIELD

The present disclosure relates to a scroll compressor. More specifically, the present disclosure relates to a scroll compressor including a silencing chamber.

BACKGROUND ART

Scroll compressors include a compression mechanism with a compression chamber formed by a combination of a fixed scroll and an orbiting scroll. Refrigerant is compressed in the compression chamber. Refrigerant pulsations may occur as the compressed refrigerant is discharged from the compression chamber to the outside of the compression chamber. Such refrigerant pulsations may cause jet noise. In the related art, a compressor disclosed below is known as a compressor including means for suppressing jet noise.

A compressor described in Patent Literature 1 includes a discharge space to receive refrigerant discharged from a compression chamber. The discharge space includes two spaces, and a communication space connecting the two spaces to each other. The discharge space thus serves as a silencing space for effectively reducing noise.

CITATION LIST

Patent Literature

Patent Literature 1: Japanese Unexamined Patent Application Publication No. 2018-053746

SUMMARY OF INVENTION

Technical Problem

If the space for receiving refrigerant discharged from the compression chamber has a circular cross-section, a circular sound field is formed within an expansion part that defines the space, and thus an acoustic resonance mode occurs at a specific frequency. This leads to reduced silencing effect of the silencing chamber including the expansion part, and consequently to increased noise. In the case of a circular sound field, an acoustic resonance mode has an antinode and a node in each of the circumferential direction and the radial direction.

In Patent Literature 1, each space defining the discharge space has a circular cross-section, and thus has rotational symmetry about the rotation axis of the compression mechanism. According to Patent Literature 1, each space has rotational symmetry as described above. Consequently, when an acoustic resonance mode having an antinode and a node in the radial direction occurs, an acoustic resonant mode having the same sound pressure distribution and whose antinode and node and antinode locations have a 90-degree phase shift relative to the above-mentioned acoustic resonance mode occurs at a frequency very close to the frequency at which the above-mentioned acoustic resonance mode occurs. As a result, according to Patent Literature 1,

2

the following acoustic resonance modes occur at frequencies very close to each other: an acoustic resonance mode with a sound pressure distribution whose antinode is positioned at the location of a main port, which is a discharge hole for refrigerant provided in the fixed scroll; and an acoustic resonance mode with a node positioned at the location of the main port. This leads to reduced silencing effect of the silencing space, and consequently to the inability to reduce noise resulting from refrigerant pulsations.

10 In a scroll compressor, working gas within the compression chamber may become over-compressed. The resulting excessive compression load on compressor bearings may cause the scroll compressor to malfunction. To prevent this, the fixed scroll of the scroll compressor includes, in addition to a main port, a sub-port through which the working gas over-compressed in the compression chamber is to be discharged. A need exists to reduce noise resulting from refrigerant pulsations for such a scroll compressor of a multi-port type including a main port and a sub-port.

15 20 The present disclosure has been made in view of the problem mentioned above. Accordingly, it is an object of the present disclosure to provide a scroll compressor of a multi-port type that allows for reduced noise resulting from refrigerant pulsations.

Solution to Problem

25 A scroll compressor according to an embodiment of the present disclosure includes a compression mechanism with a compression chamber. The compression chamber is formed by a combination of a fixed scroll and an orbiting scroll, and configured to compress working gas. The fixed scroll includes a main port, and a plurality of sub-ports. The main port is a port through which the working gas compressed in the compression chamber is to be discharged. The sub-ports are ports through which the working gas over-compressed in the compression chamber is to be discharged. The scroll compressor includes a rotary shaft, and a silencing chamber. The rotary shaft drives the compression mechanism. The silencing chamber is disposed downstream of the main port with respect to the flow of the working gas. The silencing chamber includes a discharge hole, an expansion part, and a plurality of chamber sub-ports. The discharge hole is a hole through which the working gas is to be discharged out of the silencing chamber. The expansion part is located upstream of the discharge hole. The expansion part is a recess that defines a space communicating with the main port. The chamber sub-ports each communicate with the corresponding one of the sub-ports. The expansion part is disposed between two of the chamber sub-ports. As seen in the axial direction of the rotary shaft, the expansion part is 30 35 40 45 50 larger than the main port, and has a flattened shape.

Advantageous Effects of Invention

According to an embodiment of the present disclosure, the expansion part of the silencing chamber has a flattened shape as seen in the axial direction. The sound field formed by the expansion part thus has rotational asymmetry, which ensures frequency separation between acoustic resonance modes having the same sound pressure distribution and whose antinode and node locations have a 90-degree phase shift relative to each other. This helps to prevent an antinode of an acoustic resonance mode from being positioned at the discharge hole of the silencing chamber in the scroll compressor, and consequently to reduce noise resulting from refrigerant pulsations.

BRIEF DESCRIPTION OF DRAWINGS

FIG. 1 is a schematic cross-sectional view of a scroll compressor according to Embodiment 1.

FIG. 2 is an enlarged schematic cross-sectional view of an area corresponding to a compression mechanism of the scroll compressor according to Embodiment 1.

FIG. 3 is a plan view, as seen in the axial direction from a fixed scroll, of a silencing chamber according to Embodiment 1.

FIG. 4 is a cross-sectional illustration for explaining the shape of an expansion part of the silencing chamber according to Embodiment 1.

FIG. 5 illustrates an acoustic analysis model of the silencing chamber according to Embodiment 1.

FIG. 6 is a plan view, as seen in the axial direction from the fixed scroll, of a silencing chamber including an expansion part according to Comparative Example.

FIG. 7 illustrates an acoustic analysis model of the silencing chamber according to Comparative Example.

FIG. 8 is a graph representing the characteristics of the acoustic analysis results on the expansion part of the silencing chamber according to Embodiment 1 and on the expansion part of the silencing chamber according to Comparative Example, illustrating the amount of noise reduction with respect to frequency.

FIG. 9 conceptually illustrates the sound pressure distribution of an acoustic resonance mode in the expansion part of the silencing chamber according to Comparative Example.

FIG. 10 conceptually illustrates the sound pressure distribution of an acoustic resonance mode in the expansion part of the silencing chamber according to Comparative Example.

FIG. 11 conceptually illustrates the sound pressure distribution of an acoustic resonance mode in the expansion part of the silencing chamber according to Embodiment 1.

FIG. 12 conceptually illustrates the sound pressure distribution of an acoustic resonance mode in the expansion part of the silencing chamber according to Embodiment 1.

FIG. 13 conceptually illustrates the sound pressure distribution of an acoustic resonance mode in the expansion part of the silencing chamber according to Embodiment 1.

FIG. 14 is a graph related to the positioning of the expansion part of the silencing chamber according to Embodiment 1, illustrating how the cross-sectional area of the expansion part changes as an angle θ is changed in increments of 5 degrees within a range of 0 degrees to 180 degrees.

FIG. 15 is a plan view, as seen in the axial direction from the fixed scroll, of a silencing chamber according to Embodiment 2.

FIG. 16 is an illustration for explaining how the shape of an expansion part of the silencing chamber according to Embodiment 2 is defined.

FIG. 17 illustrates an acoustic analysis model that is an extraction of the expansion part of the silencing chamber according to Embodiment 2.

FIG. 18 is a graph representing the characteristics of the acoustic analysis results on the expansion part of the silencing chamber according to Embodiment 2, illustrating the amount of noise reduction with respect to frequency.

FIG. 19 conceptually illustrates the sound pressure distribution of an acoustic resonance mode in the expansion part of the silencing chamber according to Embodiment 2.

FIG. 20 conceptually illustrates the sound pressure distribution of an acoustic resonance mode in the expansion part of the silencing chamber according to Embodiment 2.

FIG. 21 conceptually illustrates the sound pressure distribution of an acoustic resonance mode in the expansion part of the silencing chamber according to Embodiment 2.

FIG. 22 conceptually illustrates the sound pressure distribution of an acoustic resonance mode in the expansion part of the silencing chamber according to Embodiment 2.

FIG. 23 is a plan view, as seen in the axial direction from the fixed scroll, of a silencing chamber according to Embodiment 3.

FIG. 24 is an illustration for explaining how the shape of an expansion part of the silencing chamber according to Embodiment 3 is defined.

FIG. 25 illustrates an acoustic analysis model that is an extraction of the expansion part of the silencing chamber according to Embodiment 3.

FIG. 26 is a graph representing the characteristics of the acoustic analysis results on the expansion part 61 of the silencing chamber 60 according to Embodiment 3, illustrating the amount of noise reduction with respect to frequency.

FIG. 27 conceptually illustrates the sound pressure distribution of an acoustic resonance mode in the expansion part of the silencing chamber according to Embodiment 3.

FIG. 28 conceptually illustrates the sound pressure distribution of an acoustic resonance mode in the expansion part of the silencing chamber according to Embodiment 3.

FIG. 29 conceptually illustrates the sound pressure distribution of an acoustic resonance mode in the expansion part of the silencing chamber according to Embodiment 3.

FIG. 30 is a plan view, as seen in the axial direction from the fixed scroll, of a silencing chamber according to Embodiment 4.

FIG. 31 is an illustration for explaining how the shape of an expansion part of the silencing chamber according to Embodiment 4 is defined.

FIG. 32 illustrates an acoustic analysis model that is an extraction of the expansion part of the silencing chamber according to Embodiment 4.

FIG. 33 is a graph illustrating the characteristics of the acoustic analysis results for the expansion part of the silencing chamber according to Embodiment 4, illustrating the amount of noise reduction with respect to frequency.

FIG. 34 conceptually illustrates the sound pressure distribution of an acoustic resonance mode in the expansion part of the silencing chamber according to Embodiment 4.

FIG. 35 conceptually illustrates the sound pressure distribution of an acoustic resonance mode in the expansion part of the silencing chamber according to Embodiment 4.

FIG. 36 conceptually illustrates the sound pressure distribution of an acoustic resonance mode in the expansion part of the silencing chamber according to Embodiment 4.

FIG. 37 conceptually illustrates the sound pressure distribution of an acoustic resonance mode in the expansion part of the silencing chamber according to Embodiment 4.

DESCRIPTION OF EMBODIMENTS

Embodiment 1

Structure According to Embodiment 1

FIG. 1 is a schematic cross-sectional view of a scroll compressor 100 according to Embodiment 1. FIG. 2 is an enlarged schematic cross-sectional view of an area corresponding to a compression mechanism 12 of the scroll

compressor 100 according to Embodiment 1. Referring to FIGS. 1 and 2, the scroll compressor 100 sucks in refrigerant, which circulates in a refrigeration cycle system, through a suction pipe 2, and compresses the refrigerant in the compression mechanism 12 into a high-temperature, high-pressure state before discharging the resulting refrigerant through a discharge pipe 3. As illustrated in FIG. 1, the scroll compressor 100 includes a shell 1, an electric motor element 6, the compression mechanism 12, and a rotary shaft 13.

The shell 1 defines the outline of the scroll compressor 100. The shell 1 has a cylindrical shape. The shell 1 includes a lower shell 1a, a mid-shell 1b, and an upper shell 1c. The lower shell 1a is positioned at the bottom of the shell 1. The mid-shell 1b is welded to the lower shell 1a, and has a cylindrical shape. The upper shell 1c closes off the opening at the top of the mid-shell 1b. The suction pipe 2 is disposed at a side portion of the mid-shell 1b. The suction pipe 2 allows the working gas to be sucked into the shell 1. The discharge pipe 3 is disposed at a top portion of the upper shell 1c. The discharge pipe 3 allows the working gas to be discharged to the outside of the shell 1.

The electric motor element 6 includes a stator 4, and a rotor 5. The stator 4 is secured to the shell 1 by shrink-fitting or other methods. The rotor 5 is secured to the rotary shaft 13 by shrink-fitting or other methods. Upon supply of power to the stator 4, the rotor 5 rotates in response to a torque exerted from a rotating magnetic field generated in the stator 4. The rotation of the rotor 5 causes the rotary shaft 13 to be driven. The resulting driving force is transmitted to an orbiting scroll 10 described later. The orbiting scroll 10 makes an orbital movement while having its rotation prevented or reduced by an Oldham mechanism (not illustrated).

A balancer 30 is mounted to the rotary shaft 13. The balancer 30 is located between a frame 8 described later and the rotor 5. The balancer 30 serves to counterbalance an imbalance caused by the orbital movement of the orbiting scroll 10.

The frame 8 is disposed above the electric motor element 6 inside the shell 1. The frame 8 is secured to the shell 1. The frame 8 supports a fixed scroll 7, and the orbiting scroll 10. The frame 8 includes a suction port 11. The working gas flows into a compression chamber 9 described later through the suction port 11.

The compression mechanism 12 is disposed inside the shell 1 to compress the working gas flowing into the compression mechanism 12 through the suction port 11 as the electric motor element 6 is driven. The compression mechanism 12 is accommodated in the space inside the frame 8. The compression mechanism 12 includes the fixed scroll 7, and the orbiting scroll 10. The compression mechanism 12 includes the compression chamber 9, which is formed as the fixed scroll 7 and the orbiting scroll 10 are combined with each other in the axial direction of the rotary shaft 13 (hereinafter, simply “axial direction”). In the compression mechanism 12, as the rotary shaft 13 rotates, the compression chamber 9 moves with its volume decreasing from a radially outer portion toward a radially inner portion. The working gas within the compression chamber 9 is thus compressed.

The fixed scroll 7 is secured to the interior of the shell 1. The fixed scroll 7 is disposed over the frame 8. The fixed scroll 7 includes a main port 19, and sub-ports 20. The main port 19 is a port through which the working gas compressed in the compression chamber 9 is to be discharged. The sub-ports 20 are ports through which the working gas over-compressed in the compression chamber 9 is to be

discharged. The main port 19 and the sub-ports 20 each extend through the fixed scroll 7 in the axial direction. A single main port 19 is provided in a central portion of the fixed scroll 7, and a plurality of sub-ports 20 are provided at 5 radially outer locations relative to the main port 19.

A silencing chamber 15 is disposed on the fixed scroll 7 at a location downstream of the main port 19. The silencing chamber 15 is disposed on an end face of the fixed scroll 7 opposite from the orbiting scroll 10. The silencing chamber 15 is provided so that noise caused by the working gas blowing out of the main port 19 is reduced while the working gas communicates with the interior of the silencing chamber 15. A silencing muffler 14 is disposed at an end face of the silencing chamber 15 opposite from the fixed scroll 7, such that the silencing muffler 14 covers a discharge hole 16 and chamber sub-ports 18, which will be described later, of the silencing chamber 15. The silencing muffler 14 is provided so that noise caused by the working gas blowing out from the discharge hole 16 of the silencing chamber 15 is reduced before the working gas is blown out from an outlet hole 23 provided in the silencing muffler 14.

The silencing chamber 15 is a plate-shaped component. The silencing chamber 15 includes the discharge hole 16, and an expansion part 17. The discharge hole 16 is a hole through which the working gas is to be discharged to the outside of the silencing chamber 15. The expansion part 17 is disposed upstream of the discharge hole 16, and communicates with the discharge hole 16. The expansion part 17 is provided at a face of the silencing chamber 15 near the fixed scroll 7. The expansion part 17 is in the form of a recess defining a space that communicates with the main port 19. The expansion part 17 allows silencing to be performed by causing a sound wave to be reflected within the expansion part 17, and causing the reflected sound wave and a new incoming sound wave to interfere with each other. High-pressure working gas discharged from the main port 19 flows into the expansion part 17 of the silencing chamber 15. After passing through the expansion part 17, the working gas is discharged through the discharge hole 16 to the space 20 inside the silencing muffler 14.

The silencing chamber 15 includes the chamber sub-ports 18 communicating with the corresponding sub-ports 20 of the fixed scroll 7. The same number of chamber sub-ports 18 as the number of sub-ports 20 are provided. The working gas 45 becomes over-compressed under an operating condition in which the compression ratio is below an optimum compression ratio. Such over-compressed working gas flows from the compression chamber 9 into the chamber sub-ports 18 via the corresponding sub-ports 20 before reaching the center of the spiral. After entering the chamber sub-ports 18, the working gas is discharged to the space inside the silencing muffler 14.

A discharge valve 21 for opening and closing the discharge hole 16, and a valve guard 22 are disposed at a 55 downstream end portion of the discharge hole 16 of the silencing chamber 15 with respect to the flow of refrigerant. Likewise, a discharge valve 21 for opening and closing the chamber sub-port 18, and a valve guard 22 are disposed at a downstream end portion of each chamber sub-port 18 of the silencing chamber 15 with respect to the flow of refrigerant. The working gas that has been compressed within the compression chamber 9 pushes up the discharge valve 21, which causes the working gas to be discharged to the space inside the silencing muffler 14. After being discharged to the space inside the silencing muffler 14, the working gas is introduced to the space between the upper shell 1c and the silencing muffler 14 by passing through the outlet hole 23

provided in the silencing muffler 14. The working gas is then discharged from the discharge pipe 3 to the outside of the scroll compressor 100.

As described above, the scroll compressor 100 employs a combination of the silencing chamber 15 and the silencing muffler 14 to achieve noise reduction.

According to Embodiment 1, jet noise resulting from pressure pulsations can be reduced through appropriate positioning and shaping of the expansion part 17 of the silencing chamber 15. This is now described below.

FIG. 3 is a plan view, as seen in the axial direction from the fixed scroll 7, of the silencing chamber 15 according to Embodiment 1. In FIG. 3, the dashed line represents the main port 19. FIG. 4 is a cross-sectional illustration for explaining the shape of the expansion part of the silencing chamber 15 according to Embodiment 1.

As illustrated in FIGS. 3 and 4, as seen in the axial direction of the rotary shaft 13, the expansion part 17 is larger than the main port 19 and smaller than the outer circumferential portion of the silencing chamber 15. As seen in the axial direction, the expansion part 17 is disposed between any two of the chamber sub-ports 18. The expansion part 17 has a flattened shape 101 as seen in the axial direction. That is, the cross-sectional shape of the expansion part 17 taken along a plane orthogonal to the rotary shaft 13 is the flattened shape 101. As used herein, the term "cross-sectional shape" or "cross-sectional area" refers to a cross-sectional shape or a cross-sectional area taken along a plane orthogonal to the rotary shaft 13. The flattened shape 101 refers to a generally flat shape having a major axis and a minor axis. Embodiment 1 is directed to an example in which the flattened shape 101 is an ellipse.

As illustrated in FIG. 4, the expansion part 17 is positioned such that a longitudinal direction 103 of a rectangle 102 circumscribing the flattened shape 101, and a straight line 104 connecting the respective centers of the chamber sub-ports 18 form an angle θ that satisfies the condition that $45^\circ \leq \theta \leq 135^\circ$. The rectangle 102 has a length 12 in the longitudinal direction that is greater than the shortest distance between two chamber sub-ports 18. The length 12 in the longitudinal direction of the rectangle 102 is greater than or equal to five times the length 11 in the transverse direction of the rectangle 102, and less than the diameter of the silencing chamber 15. The length 11 in the transverse direction of the rectangle 102 is less than the shortest distance between two chamber sub-ports 18. The shortest distance between two chamber sub-ports 18 corresponds to the "length of the straight line 104" minus twice the "radius of each chamber sub-port." Examples of the flattened shape 101 include a rectangle. That is, examples of the expansion part 17 include an expansion part having a rectangular shape as seen in the axial direction.

The main port 19 and the discharge hole 16 lie on a central axis 105 that divides the rectangle 102 in two in the transverse direction.

Operation and Effects According to Embodiment 1

The silencing chamber 15 serves as a silencer used to address noise. Silencers can be roughly classified into the following two types: absorptive and reactive. Absorptive silencers utilize a fibrous or porous sound-absorbing material or other materials to absorb acoustic energy within a conduit. By contrast, reactive silencers utilize reflections or interferences of sound waves. The silencing chamber 15 corresponds to a reactive silencer.

Several methods exist to evaluate the silencing effect of silencers. In the following description, the silencing effect is evaluated based on the amount of noise reduction NR. The amount of noise reduction NR is defined as the difference between a sound pressure level L_{p1} at the silencer inlet, and a sound pressure level L_{p2} at the silencer outlet. The amount of noise reduction NR is given by Equation (1).

10 [Math. 1]

$$NR = L_{p1} - L_{p2} \quad (1)$$

Equation (1) indicates that when the amount of noise reduction NR is positive, the sound pressure level (L_{p2}) at the silencer outlet is lower than the sound pressure level (L_{p1}) at the silencer inlet, and thus noise has been suppressed by the silencer. That is, the greater the amount of noise reduction NR, the greater the silencing effect provided by the silencer.

In the following description, the silencing effect is evaluated by a method including performing a computer simulation by use of an acoustic analysis model of the expansion part 17 of the silencing chamber 15, and calculating the respective sound pressure levels at the inlet and outlet of the silencing chamber 15, and the sound pressure distributions of acoustic resonance modes that occur within the silencing chamber 15.

FIG. 5 illustrates an acoustic analysis model 17a of the silencing chamber 15 according to Embodiment 1. FIG. 6 is a plan view, as seen in the axial direction from the fixed scroll, of a silencing chamber 33 including an expansion part 31 according to Comparative Example. The silencing chamber 33 according to Comparative Example is a silencing chamber with the expansion part 31 whose cross-section has a circular shape 32. That is, as seen in the axial direction, the silencing chamber 33 is a silencing chamber whose expansion part has the circular shape 32. FIG. 7 illustrates an acoustic analysis model 31a of the silencing chamber 33 according to Comparative Example. The expansion part 17 according to Embodiment 1 has a cross-sectional area equal to the cross-sectional area of the expansion part 31 according to Comparative Example. In the following description, the silencing effect of the silencing chamber 15 according to Embodiment 1 is compared with the silencing effect of the silencing chamber 33 according to Comparative Example.

The acoustic analysis model 17a is a model in which the expansion part 17 of the silencing chamber 15 is filled with finite elements, and in which the main port 19 serves as an input face and the discharge hole 16 serves as an outlet face. The acoustic analysis model 31a is a model in which the expansion part 31 of the silencing chamber 33 is filled with finite elements, and in which the main port 19 serves as an input face and the discharge hole 16 serves as an outlet face. An acoustic analysis was conducted using the acoustic analysis models 17a and 31a. The analysis was conducted using the following conditions: a particle velocity of 1 [m/s] was given to the input face; air was used as fluid; the acoustic velocity c was 340 [m/s]; and the air density ρ was 1.225 [kg/m³]. The amount of noise reduction NR was calculated by substitution of the sound pressure level L_{p1} at the input face and the sound pressure level L_{p2} at the outlet face into Equation (1).

FIG. 8 described below illustrates the results of the analyses performed using the acoustic analysis model 17a illustrated in FIG. 5 and the acoustic analysis model 31a illustrated in FIG. 6.

FIG. 8 is a graph representing the characteristics of the acoustic analysis results on the expansion part 17 of the silencing chamber 15 according to Embodiment 1 and on the expansion part 31 of the silencing chamber 33 according to Comparative Example, illustrating the amount of noise reduction with respect to frequency. In FIG. 8, the solid line represents the characteristics according to Embodiment 1, and the dashed line represents the characteristics according to Comparative Example. As illustrated in FIG. 8, according to Embodiment 1, the amount of noise reduction is positive within a frequency band 41. That is, Embodiment 1 provides a silencing effect over the frequency band 41, which covers a wide range of frequencies. However, Comparative Example exhibits a decrease in the amount of noise reduction due to the presence of a dip 42.

FIGS. 9 and 10 each illustrate an acoustic resonance mode that was confirmed to occur in the expansion part 31 as a result of the simulation performed using the acoustic analysis model 31a illustrated in FIG. 7.

FIGS. 9 and 10 each conceptually illustrate the sound pressure distribution of an acoustic resonance mode in the expansion part 31 of the silencing chamber 33 according to Comparative Example. FIGS. 11, 12, and 13 each conceptually illustrate the sound pressure distribution of an acoustic resonance mode in the expansion part 17 of the silencing chamber 15 according to Embodiment 1. In FIGS. 9 to 13, “+” and “-” represent antinodes of acoustic resonance modes, and thin lines represent nodes.

As illustrated in FIGS. 9 and 10, it was confirmed from the simulation results that in the silencing chamber 33 according to Comparative Example, two acoustic resonance modes each having a single node in the radial direction occur very close to each other at the frequency of the dip 42. That is, in the silencing chamber 33 according to Comparative Example, acoustic resonance modes occur that have the same sound pressure distribution and whose antinode and node locations have a 90-degree phase shift relative to each other. This is because the expansion part 31 according to Comparative Example has a circular cross-sectional shape, and thus the sound field formed by the expansion part 31 has rotational symmetry about the rotary shaft 13. In the acoustic resonance mode illustrated in FIG. 10, the discharge hole 16 is positioned at a node. This results in increased amount of noise reduction. In the acoustic resonance mode illustrated in FIG. 9, however, the discharge hole 16 is positioned at an antinode. This results in decreased amount of noise reduction. As used herein, the term “radial direction” representing the direction of a node refers to the direction of a straight line connecting two points on the outer circumference of an acoustic resonance mode.

In the silencing chamber 33 according to Comparative Example, the acoustic resonance mode illustrated in FIG. 9 and the acoustic resonance mode illustrated in FIG. 10 occur in sequence. Accordingly, the acoustic resonance mode illustrated in FIG. 10 allows for increased amount of noise reduction due to the discharge hole 16 of the silencing chamber 33 being positioned at a node of the acoustic resonance mode. However, the acoustic resonance mode illustrated in FIG. 9 occurs at a frequency very close to the frequency at which the acoustic resonance mode illustrated in FIG. 10 has occurred. In the acoustic resonance mode illustrated in FIG. 9, the discharge hole 16 is positioned at an antinode, and thus the dip 42 occurs, leading to decreased amount of noise reduction. This results in reduced silencing effect of the silencing chamber 33 according to Comparative Example. That is, when acoustic resonance modes each exhibiting a sound pressure distribution with a single node

occur consecutively, this results in the discharge hole 16 being positioned at an antinode in one of the two consecutive acoustic resonance modes. This causes the dip 42 to occur, leading to decreased amount of noise reduction.

5 In the silencing chamber 15 according to Embodiment 1, by contrast, three acoustic resonance modes occur as illustrated in FIGS. 11 to 13. FIG. 11 depicts an acoustic resonance mode that occurs at a frequency below the frequency band 41, and that has a sound pressure distribution 10 with a single node in the radial direction. FIG. 12 depicts an acoustic resonance mode that occurs at a frequency within the frequency band 41, and that has a sound pressure distribution with two nodes in the radial direction. FIG. 13 15 depicts an acoustic resonance mode that occurs at a frequency within the frequency band 41, and that has a sound pressure distribution with a single node in the radial direction.

In the silencing chamber 15, the following acoustic resonance modes occur in sequence: the acoustic resonance 20 mode with a sound pressure distribution having a single node in the radial direction (FIG. 11); the acoustic resonance mode with a sound pressure distribution having two nodes in the radial direction (FIG. 12); and the acoustic resonance mode with a sound pressure distribution having a single node in the radial direction (FIG. 13). As described above, 25 in the silencing chamber 15 according to Embodiment 1, acoustic resonance modes each exhibiting a sound pressure distribution with a single node do not occur consecutively. This is because the expansion part 17 has a flattened cross-sectional shape, and thus the sound field formed by the 30 expansion part 17 has rotation asymmetry.

For the configuration in which the discharge hole 16 is positioned at a node of the sound pressure distribution of an acoustic resonance mode having two nodes in the radial direction 35 35 as illustrated in FIGS. 12 and 13, acoustic resonance modes occurred consecutively that each have a sound pressure distribution with a node positioned at the discharge hole 16. Consequently, as illustrated in FIG. 8, the amount of noise reduction provided by the silencing chamber 15 can 40 be maintained positive over the wide frequency band 41, leading to increased silencing effect. That is, due to the expansion part 17 of the silencing chamber 33 being formed in a flattened shape as seen in the axial direction, the scroll compressor 100 allows for reduced jet noise resulting from 45 pressure pulsations.

Reference is now made to the effect of positioning the expansion part 17 in such a way that satisfies the condition that $45^\circ \leq \theta \leq 135^\circ$.

FIG. 14 is a graph related to the positioning of the 50 expansion part 17 of the silencing chamber 15 according to Embodiment 1, illustrating how the cross-sectional area of the expansion part 17 changes as the angle θ is changed in increments of 5 degrees within a range of 0 degrees to 180 degrees. The horizontal axis represents the angle θ [degrees]. The vertical axis represents the cross-sectional area normalized by the cross-sectional area when the angle θ is 55 90 degrees representing the maximum cross-sectional area. The cross-sectional area along the vertical axis is calculated based on a relational expression in which the expansion part 17 has a fixed length in the direction of the major axis, and has a length in the direction of the minor axis that changes 60 with changes in the angle θ .

As described above, the cross-sectional area of the expansion part 17 changes with changes in the angle θ . This is due 65 to the reason described below. The expansion part 17 is necessarily required to be positioned between two chamber sub-ports 18. Although it is possible to cause the expansion

11

part 17 to rotate while keeping the same cross-sectional area, eventually an angle is reached where the expansion part 17 comes into interference with the two chamber sub-ports 18. At this time, if the length of the expansion part 17 in the major-axis direction is fixed to maintain a high degree of flattening, reducing the length of the expansion part 17 in the minor-axis direction allows the expansion part 17 to be positioned between the two chamber sub-ports 18 in the scroll compressor 100. That is, if the angle θ is within a range that satisfies the condition that 45 degrees $\leq \theta \leq 135$ degrees, reducing the length of the expansion part 17 in the minor-axis direction allows the expansion part 17 to be positioned between the two chamber sub-ports 18 in the scroll compressor 100. This makes it possible to prevent a decrease in the amount of noise reduction. Although the expansion part 17 may be caused to rotate while maintaining the same cross-sectional area, in that case, the expansion part 17 needs to be positioned to avoid interference with the two chamber sub-ports 18.

It is appreciated from FIG. 14 that when the angle θ satisfies the condition that 45 degrees $\leq \theta \leq 135$ degrees, the cross-sectional area of the expansion part 17 is greater than or equal to 70% of the maximum cross-sectional area. The silencing effect of a silencer increases with increasing cross-sectional area of the expansion part relative to the cross-sectional area of the input face. Accordingly, designing the expansion part 17 within the angular range mentioned above makes it possible to prevent a decrease in the amount of noise reduction.

Reference is now made to the effect of making the aspect ratio between the major and minor axes of the flattened shape 101 of the expansion part 17 greater than or equal to 5:1.

When the aspect ratio between the major and minor axes of the flattened shape 101 of the expansion part 17 is greater than or equal to 5:1, the separation between acoustic resonance modes with the same sound pressure distribution can be increased for the reason described below. Increased separation between acoustic resonance modes means that the respective frequencies at which these acoustic resonance modes occur are far apart from each other.

A flattening e , which is a numerical value representing the degree of flattening of a flattened shape, is given by Equation (2) below.

[Math. 2]

$$e = 1 - b/a \quad (2)$$

In Equation (2), "a" denotes the radius of the major axis, and "b" denotes the radius of the minor axis. The closer the value of the flattening e is to 1, the greater the degree of flattening. A low degree of flattening causes the above-mentioned separation between acoustic resonance modes to decrease, with the result that acoustic resonance modes with the same sound pressure distribution occur at frequencies very close to each other. A high degree of flattening, by contrast, allows the above-mentioned separation between acoustic resonance modes to be increased.

In this regard, an aspect ratio of greater than or equal to 5:1 translates to a flattening e of greater than or equal to 0.8. This means that the degree of flattening is greater than 0.5, which is the middle value of flattening. Therefore, an aspect ratio of greater than or equal to 5:1 allows for increased separation between acoustic resonance modes having the

12

same sound pressure distribution. Specifically, the frequency separation between acoustic resonance modes with the same sound pressure distribution is greater than or equal to 1×kHz. As described above, increasing the degree of flattening allows for increased separation between acoustic resonance modes with the same sound pressure distribution. This allows the amount of noise reduction to be maintained positive over the wide frequency band 41, leading to increased silencing effect.

10 A decrease in the cross-sectional area of the discharge hole 16 results in a decrease in the flow rate of working gas passing through the interior of the silencing chamber 15. This leads to decreased efficiency. In this regard, setting the angle θ within the range mentioned above allows the expansion part 17 to have a relatively large cross-sectional area. The above-mentioned configuration therefore makes it possible to reduce jet noise resulting from pressure pulsations while maintaining efficiency, without requiring a decrease in the cross-sectional area of the discharge hole 16.

15 20 As described above, the scroll compressor 100 according to Embodiment 1 is the scroll compressor 100 of a multi-port type including the main port 19 and the sub-ports 20, with the expansion part 17 of the silencing chamber 15 having a flattened shape as seen in the axial direction. The sound field 25 formed by the expansion part 17 thus has rotational asymmetry, which ensures frequency separation between acoustic resonance modes having the same sound pressure distribution and whose node and antinode locations have a 90-degree phase shift relative to each other. This helps to prevent 30 an antinode of an acoustic resonance mode from being positioned at the discharge hole 16 of the silencing chamber 15, and consequently to mitigate a decrease in silencing effect. As a result, noise resulting from refrigerant pulsations in the scroll compressor 100 of a multi-port type can be 35 reduced.

In the scroll compressor 100, as seen in the axial direction, the rectangle 102 circumscribing the flattened shape has a length in the longitudinal direction that is greater than the shortest distance between two chamber sub-ports 18. As a 40 result, the degree of flattening of the expansion part 17 can be increased to increase the separation between acoustic resonance modes. This makes it possible to prevent a decrease in the amount of noise reduction in the scroll compressor 100.

45 As described above, as seen in the axial direction, the main port 19 and the discharge hole 16 lie on the central axis 105 in the transverse direction of the rectangle 102. This makes it possible to position the discharge hole 16 at a node of an acoustic resonance mode that occurs in the expansion part 17, and consequently to prevent a decrease in the amount of noise reduction in the scroll compressor 100.

50 As seen in the axial direction, the longitudinal direction of the rectangle circumscribing the flattened shape of the expansion part 17, and the straight line connecting the 55 respective centers of two chamber sub-ports 18 form the angle θ that satisfies the condition that 45 degrees $\leq \theta \leq 135$ degrees. This makes it possible to prevent a decrease in the amount of noise reduction in the scroll compressor 100.

60 Embodiment 2

Structure of Embodiment 2

65 Embodiment 2 differs from Embodiment 1 in the cross-sectional shape of the expansion part of the silencing chamber. Embodiment 2 is described below with focus on features different from those according to Embodiment 1, and fea-

tures not described with reference to Embodiment 2 below are similar or identical to those according to Embodiment 1.

FIG. 15 is a plan view, as seen in the axial direction from the fixed scroll 7, of a silencing chamber 50 according to Embodiment 2. FIG. 16 is an illustration for explaining how the shape of an expansion part 51 of the silencing chamber 50 according to Embodiment 2 is defined.

The expansion part 51 of the silencing chamber 50 according to Embodiment 2 has a flattened shape 201 as seen in the axial direction. The flattened shape 201 is obtained by connecting the outlines of two flattened shapes positioned to partially overlap each other. Although FIG. 16 depicts an example in which one of the two flattened shapes constituting the flattened shape 201 is positioned such that the one flattened shape is rotated relative to the other flattened shape about the center of the other flattened shape, this is not to be construed restrictively. In another example, one of the two flattened shapes constituting the flattened shape 201 may be positioned such that the one flattened shape is a translation of the other flattened shape. Although the flattened shape 201 is depicted in the example in FIG. 16 as being made up of two flattened shapes, the flattened shape 201 may be made up of three or more flattened shapes. In short, the flattened shape 201 may be any shape obtained by connecting the outlines of a plurality of flattened shapes positioned to partially overlap each other. The following describes how the shape of the expansion part 51 is defined for an example in which the flattened shape is made up of two flattened shapes. Of the two flattened shapes, one is referred to as a flattened shape 201a, and the other is referred to as a flattened shape 201b.

The flattened shape 201a is positioned such that a longitudinal direction 203a of a rectangle 202a circumscribing the flattened shape 201a, and a straight line 204 connecting the respective centers of the chamber sub-ports 18 form an angle θ_1 that satisfies the condition that $45^\circ \leq \theta_1 \leq 135^\circ$. The flattened shape 201b is positioned such that a longitudinal direction 203b of a rectangle 202b circumscribing the flattened shape 201b, and the straight line 204 connecting the respective centers of the chamber sub-ports 18 form an angle θ_2 that satisfies the condition that $45^\circ \leq \theta_2 \leq 135^\circ$. The minor axis of the flattened shape 201 has a length l_1 less than the shortest distance between two chamber sub-ports 18. The length l_1 of the minor axis of the flattened shape 201 is the length in the transverse direction of the rectangle circumscribing the flattened shape 201. The main port 19 and the discharge hole 16 lie on a central axis that divides one of the rectangle 202a and the rectangle 202b in two in the transverse direction.

Operation and Effects According to Embodiment 2

FIG. 17 illustrates an acoustic analysis model 51a that is an extraction of the expansion part 51 of the silencing chamber 50 according to Embodiment 2. The expansion part 51 has a cross-sectional area equal to the cross-sectional area of the expansion part 17 according to Embodiment 1. The acoustic analysis model 51a is a model in which the expansion part 51 of the silencing chamber 50 is filled with finite elements, and in which the main port 19 serves as an input face and the discharge hole 16 serves as an outlet face. An acoustic analysis was conducted using the acoustic analysis model 51a. The analysis was conducted using the following conditions: a particle velocity of 1 [m/s] was given to the input face; air was used as fluid; the acoustic velocity c was 340 [m/s]; and the air density ρ was 1.225 [kg/m³]. The amount of noise reduction NR was calculated by substitution

of the sound pressure level L_{p1} at the input face and the sound pressure level L_{p2} at the outlet face into Equation (1) mentioned above.

FIG. 18 is a graph representing the characteristics of the acoustic analysis results on the expansion part 51 of the silencing chamber 50 according to Embodiment 2, illustrating the amount of noise reduction with respect to frequency. As illustrated in FIG. 18, the amount of noise reduction in the expansion part 51 is positive within a frequency band 43. 10 That is, Embodiment 2 provides a silencing effect over the frequency band 43, which covers a wide range of frequencies. A dip 44 is observed to occur in FIG. 18. The dip 44 will be described later.

FIGS. 19 to 22 each conceptually illustrate the sound pressure distribution of an acoustic resonance mode in the expansion part 51 of the silencing chamber 50 according to Embodiment 2. In FIGS. 19 to 22, "+" and "-" represent antinodes of acoustic resonance modes, and thin lines represent nodes.

20 It is confirmed from the simulation results that in the silencing chamber 50 according to Embodiment 2, four acoustic resonance modes illustrated in FIGS. 19 to 22 occur in the expansion part 51. FIG. 19 depicts an acoustic resonance mode that occurs at a frequency below the frequency band 43, and that has a sound pressure distribution with a single node in the radial direction. FIG. 20 depicts an acoustic resonance mode that occurs at a frequency within the frequency band 43, and that has a sound pressure distribution with two nodes in the radial direction. FIG. 21 25 depicts an acoustic resonance mode that occurs at a frequency within the frequency band 43, and that has a sound pressure distribution with a single node in the radial direction. FIG. 22 depicts an acoustic resonance mode that occurs at a frequency within the frequency band 43, and that has a sound pressure distribution with three nodes in the radial direction.

30 In the silencing chamber 50, the following acoustic resonance modes occur in sequence: the acoustic resonance mode illustrated in FIG. 19 that has a sound pressure distribution with a single node in the radial direction; the acoustic resonance mode illustrated in FIG. 20 that has a sound pressure distribution with two nodes in the radial direction; the acoustic resonance mode illustrated in FIG. 21 that has a sound pressure distribution with a single node in the radial direction; and the acoustic resonance mode illustrated in FIG. 22 that has a sound pressure distribution with three nodes in the radial direction. As described above, in the silencing chamber 50, acoustic resonance modes each exhibiting a sound pressure distribution with a single node in the 35 radial direction, that is, the sound pressure distribution illustrated in FIG. 19 and the sound pressure distribution illustrated in FIG. 21, do not occur consecutively. This makes it possible to mitigate a decrease in the amount of noise reduction in the silencing chamber 50. The reason why sound pressure distributions each having a single node in the radial direction do not occur consecutively is that the expansion part 51 has a flattened shape and thus the sound field formed by the expansion part 51 has rotational asymmetry.

40 With regard to the configuration in which the discharge hole 16 is positioned at a node of the sound pressure distribution of an acoustic resonance mode having two nodes in the radial direction, acoustic resonance modes each having a sound pressure distribution with a node positioned 45 at the discharge hole 16 occurred consecutively as illustrated in FIGS. 20 to 22. Consequently, as illustrated in FIG. 18, the amount of noise reduction provided by the silencing

15

chamber **50** can be maintained positive over the wide frequency band **43**, leading to increased silencing effect. That is, due to the expansion part **51** of the silencing chamber **50** being formed in a flattened shape as seen in the axial direction, the scroll compressor **100** allows for reduced jet noise resulting from pressure pulsations.

Although the silencing chamber **50** provides a significant silencing effect, the expansion part **51** exhibits the dip **44** due to the presence of an acoustic resonance mode with a sound pressure distribution having three nodes in the radial direction. This is because the discharge hole **16** is displaced relative to the corresponding node in the acoustic resonance mode illustrated in FIG. 22. Specifically, the central portion of the discharge hole **16** is displaced relative to the corresponding node.

In the silencing chamber **50**, the expansion part **51** exhibits the dip **44** as described above. In this regard, the dip **44** occurs in a sound pressure distribution when the sound pressure distribution has three nodes in the radial direction. In the case of an acoustic resonance mode having a sound pressure distribution with three nodes in the radial direction, that is, the sound pressure distribution illustrated in FIG. 22, a decrease in the amount of noise reduction occurs over a narrow frequency band, unlike with a mode in which the major part of the discharge hole **16** is positioned at an antinode of the sound pressure distribution as in the case of the acoustic resonance mode having the sound pressure distribution illustrated in FIG. 19. Accordingly, the dip **44** resulting from the acoustic resonance mode with a sound pressure distribution having three nodes in the radial direction can be reduced by means of the silencing muffler **14** located downstream of the silencing chamber **50** with respect to the flow of refrigerant.

As described above, the scroll compressor **100** according to Embodiment 2 can provide effects similar to those provided by Embodiment 1.

Embodiment 3

Structure of Embodiment 3

Embodiment 3 differs from Embodiment 1 in the shape of the expansion part of the silencing chamber. Embodiment 3 is described below with focus on features different from those according to Embodiment 1, and features not described with reference to Embodiment 3 below are similar or identical to those according to Embodiment 1.

FIG. 23 is a plan view, as seen in the axial direction from the fixed scroll **7**, of a silencing chamber **60** according to Embodiment 3. FIG. 24 is an illustration for explaining how the shape of an expansion part **61** of the silencing chamber **60** according to Embodiment 3 is defined.

The expansion part **61** of the silencing chamber **60** according to Embodiment 3 has a flattened shape **301** as seen in the axial direction. As illustrated in FIG. 24, as seen in the axial direction, the expansion part has two parts including one part and an other part, the one part having a cross-sectional area greater than a cross-sectional area of the other part, the two parts are formed by dividing the expansion part by a central axis that is a central axis in a transverse direction of a rectangle circumscribing the flattened shape. In one example, the flattened shape **301** is a shape obtained by connecting the opposite ends of an arc by a straight line as illustrated in FIGS. 23 and 24. The flattened shape **301** is positioned such that a longitudinal direction **303** of the rectangle **302** circumscribing the flattened shape **301**, and a straight line **304** connecting the respective centers of the

16

chamber sub-ports **18** form an angle θ that satisfies the condition that 45 degrees $\leq \theta \leq 135$ degrees. The main port **19** and the discharge hole **16** lie on the central axis **305**.

5 Operation and Effects According to Embodiment 3

FIG. 25 illustrates an acoustic analysis model **61a** that is an extraction of the expansion part **61** of the silencing chamber **60** according to Embodiment 3. The expansion part **61** has a cross-sectional area equal to the cross-sectional area of the expansion part **17** according to Embodiment 1. The acoustic analysis model **61a** is a model in which the expansion part **61** of the silencing chamber **60** is filled with finite elements, and in which the main port **19** serves as an input face and the discharge hole **16** serves as an outlet face. An acoustic analysis was conducted using the acoustic analysis model **61a**. The analysis was conducted using the following conditions: a particle velocity of 1 [m/s] was given to the input face; air was used as fluid; the acoustic velocity c was 340 [m/s]; and the air density ρ was 1.225 [kg/m³]. The amount of noise reduction NR was calculated by substitution of the sound pressure level L_{p1} at the input face and the sound pressure level L_{p2} at the outlet face into Equation (1) mentioned above.

FIG. 26 is a graph representing the characteristics of the acoustic analysis results on the expansion part **61** of the silencing chamber **60** according to Embodiment 3, illustrating the amount of noise reduction with respect to frequency. As illustrated in FIG. 26, the amount of noise reduction in the expansion part **61** is positive within a frequency band **45**. That is, Embodiment 3 provides a silencing effect over the frequency band **45**, which covers a wide range of frequencies.

FIGS. 27 to 29 each conceptually illustrate the sound pressure distribution of an acoustic resonance mode in the expansion part **61** of the silencing chamber **60** according to Embodiment 3. In FIGS. 27 to 29, "+" and "-" represent antinodes of acoustic resonance modes, and thin lines represent nodes.

It is confirmed from the simulation results that in the silencing chamber **60** according to Embodiment 3, three acoustic resonance modes occur in the expansion part **61** as illustrated in FIGS. 27 to 29. FIG. 27 depicts an acoustic resonance mode that occurs at a frequency below the frequency band **45**, and that has a sound pressure distribution with a single node in the radial direction. FIG. 28 depicts an acoustic resonance mode that occurs at a frequency within the frequency band **45**, and that has a sound pressure distribution with two nodes in the radial direction. FIG. 29 depicts an acoustic resonance mode that occurs at a frequency within the frequency band **45**, and that has a sound pressure distribution with a single node in the circumferential direction. As used herein, the term "circumferential direction" representing the direction of a node refers to a direction along the outer circumference of an acoustic resonance mode.

In the silencing chamber **60**, the three acoustic resonance modes illustrated in FIGS. 27 to 29 occur. No acoustic resonance mode occurs that exhibits a sound pressure distribution with a 90-degree phase shift relative to the sound pressure distribution of the acoustic resonance mode with a single node in the radial direction illustrated in FIG. 27. Consequently, an acoustic resonance mode having a sound pressure distribution with an antinode positioned at the discharge hole **16**, and an acoustic resonance mode having a sound pressure distribution with a node positioned at the discharge hole **16** do not occur at frequencies very close to

each other. As a result, a decrease in silencing effect does not occur in the silencing chamber **60**. The reason why no acoustic resonance mode occurs that exhibits a sound pressure distribution with a 90-degree phase shift relative to the sound pressure distribution of the acoustic resonance mode with a single node in the radial direction illustrated in FIG. **27** is that the sound field formed by the expansion part **61** has rotational asymmetry, and has asymmetry about the central axis **305** of the rectangle **302**.

With regard to the configuration in which the discharge hole **16** is positioned at a node of the sound pressure distribution of an acoustic resonance mode with two nodes in the radial direction, acoustic resonance modes each having a sound pressure distribution with a node positioned at the discharge hole **16** occurred consecutively as illustrated in FIGS. **28** and **29**. This means that, due to the expansion part **61** being formed in a flattened shape as seen in the axial direction, the amount of noise reduction provided by the silencing chamber **60** can be maintained positive over the wide frequency band **45** as illustrated in FIG. **26**, leading to increased silencing effect. That is, due to the expansion part **61** of the silencing chamber **60** being formed in a flattened shape as seen in the axial direction, the scroll compressor **100** allows for reduced jet noise resulting from pressure pulsations.

As described above, the scroll compressor **100** according to Embodiment 3 can provide effects similar to those provided by Embodiment 1.

Embodiment 4

Structure of Embodiment 4

Embodiment 4 differs from Embodiment 1 in the cross-sectional shape of the expansion part of the silencing chamber. Embodiment 4 is described below with focus on features different from those according to Embodiment 1, and features not described with reference to Embodiment 4 below are similar or identical to those according to Embodiment 1.

FIG. **30** is a plan view, as seen in the axial direction from the fixed scroll **7**, of a silencing chamber **70** according to Embodiment 4. FIG. **31** is an illustration for explaining how the shape of an expansion part **71** of the silencing chamber **70** according to Embodiment 4 is defined.

The expansion part **71** of the silencing chamber **70** according to Embodiment 4 has a flattened shape **401** as seen in the axial direction. More specifically, as illustrated in FIG. **31**, the flattened shape **401** is a shape that, as seen in the axial direction, is inscribed in a rectangle **402**, and has a plurality of points of contact **404** with the four sides of the rectangle **402**. The flattened shape **401** has two or more points of contact **404** with at least one side **405** of the rectangle **402**. FIGS. **30** and **31** each illustrate an example in which the flattened shape **401** has two points of contact **404** with each of two opposite sides of the rectangle. The flattened shape **401** is positioned such that a longitudinal direction **407** of the rectangle **402** circumscribing the flattened shape **401**, and a straight line **403** connecting the respective centers of the chamber sub-ports **18** form an angle θ that satisfies the condition that $45^\circ \leq \theta \leq 135^\circ$. The main port **19** and the discharge hole **16** lie on a central axis **406** that divides the rectangle **402** in two in the transverse direction.

Operation and Effects According to Embodiment 4

FIG. **32** illustrates an acoustic analysis model **71a** that is an extraction of the expansion part **71** of the silencing

chamber **70** according to Embodiment 4. The expansion part **71** has a cross-sectional area equal to the cross-sectional area of the expansion part **17** according to Embodiment 1. For the acoustic analysis model **71a**, an acoustic analysis was conducted with the expansion part **71** of the silencing chamber **70** filled with finite elements, with the main port **19** serving as an input face and the discharge hole **16** serving as an outlet face. The analysis was conducted using the following conditions: a particle velocity of 1 [m/s] was given to the input face; air was used as fluid: the acoustic velocity c was 340 [m/s]; and the air density ρ was 1.225 [kg/m³]. The amount of noise reduction NR was calculated by substitution of the sound pressure level L_{p1} at the input face and the sound pressure level L_{p2} at the outlet face into Equation (1) mentioned above.

FIG. **33** is a graph representing the characteristics of the acoustic analysis results on the expansion part **71** of the silencing chamber **70** according to Embodiment 4, illustrating the amount of noise reduction with respect to frequency. As illustrated in FIG. **33**, the amount of noise reduction in the expansion part **71** is positive within a frequency band **46**. That is, Embodiment 4 provides a silencing effect over the frequency band **46**, which covers a wide range of frequencies.

FIGS. **34** to **37** each conceptually illustrate the sound pressure distribution of an acoustic resonance mode in the expansion part of the silencing chamber according to Embodiment 4. In FIGS. **34** to **37**, "+" and "-" represent antinodes of acoustic resonance modes, and thin lines represent nodes.

In the silencing chamber **70** according to Embodiment 4, four acoustic resonance modes occur as illustrated in FIGS. **34** to **37**. FIG. **34** depicts an acoustic resonance mode that occurs at a frequency below the frequency band **46**, and that has a sound pressure distribution with a single node in the radial direction. FIG. **35** depicts an acoustic resonance mode that occurs at a frequency below the frequency band **46**, and that has a sound pressure distribution with a single node in the radial direction. FIG. **36** depicts an acoustic resonance mode that occurs at a frequency within the frequency band **46**, and that has a sound pressure distribution with two nodes in the radial direction. FIG. **37** depicts an acoustic resonance mode that occurs at a frequency within the frequency band **46**, and that has a sound pressure distribution with two nodes in the radial direction.

In the silencing chamber **70**, the following acoustic resonance modes occur in sequence: the acoustic resonance mode illustrated in FIG. **34** that has a sound pressure distribution with a single node in the radial direction; the acoustic resonance mode illustrated in FIG. **35** that has a sound pressure distribution with a single node in the radial direction; the acoustic resonance mode illustrated in FIG. **36** that has a sound pressure distribution with two nodes in the radial direction; and the acoustic resonance mode illustrated in FIG. **37** that has a sound pressure distribution with two nodes in the radial direction. This means that in the silencing chamber **70**, the following acoustic resonance modes occur consecutively: the acoustic resonance mode illustrated in FIG. **34**, which has a single node; and the acoustic resonance mode illustrated in FIG. **35**, which has a single node and which exhibits the same sound pressure distribution with a 90-degree phase shift relative to the acoustic resonance mode illustrated in FIG. **34**. It is observed from the results of a simulation, however, that the acoustic resonance mode illustrated in FIG. **34**, and the acoustic resonance mode illustrated in FIG. **35** occur with a frequency separation from each other of greater than or equal to 1 kHz. This makes it

19

possible to mitigate a decrease in the amount of noise reduction. The reason why these acoustic resonance modes occur with a frequency separation from each other of greater than or equal to 1×KHz is that the sound field formed by the expansion part 71 has rotational asymmetry.

With regard to the configuration in which the discharge hole 16 is positioned at the same node of acoustic resonance modes, that is, at a node of the sound pressure distribution of an acoustic resonance mode having a single node in the radial direction, and at a node of the sound pressure distribution of an acoustic resonance mode having two nodes in the radial direction, acoustic resonance modes each having a sound pressure distribution with a node positioned at the discharge hole 16 occurred consecutively as illustrated in FIGS. 35 to 37. Accordingly, due to the expansion part 71 being formed in a flattened shape as seen in the axial direction, the amount of noise reduction provided by the silencing chamber 70 can be maintained positive over the wide frequency band 46 as illustrated in FIG. 34, leading to increased silencing effect. That is, due to the expansion part 71 of the silencing chamber 70 being formed in a flattened shape as seen in the axial direction, the scroll compressor 100 allows for reduced jet noise resulting from pressure pulsations.

As described above, the scroll compressor 100 according to Embodiment 4 can provide effects similar to those provided by Embodiment 1.

The invention claimed is:

1. A scroll compressor including a compression mechanism, the compression mechanism including a compression chamber, the compression chamber being formed by a

20

combination of a fixed scroll and an orbiting scroll and configured to compress working gas, the fixed scroll including a main port and a plurality of sub-ports, the main port being a port through which the working gas compressed in the compression chamber is to be discharged, the plurality of sub-ports being ports through which the working gas over-compressed in the compression chamber is to be discharged, the scroll compressor comprising:

10 a rotary shaft that drives the compression mechanism; and a silencing chamber disposed downstream of the main port with respect to a flow of the working gas, wherein the silencing chamber includes

15 a discharge hole through which the working gas is to be discharged out of the silencing chamber, an expansion part located upstream of the discharge hole, the expansion part being a recess that defines a space communicating with the main port, and a plurality of chamber sub-ports each communicating with a corresponding one of the plurality of sub-ports, and

20 wherein the expansion part is disposed between two of the plurality of chamber sub-ports, the expansion part being larger than the main port and having a flattened shape as seen in an axial direction of the rotary shaft.

2. The scroll compressor of claim 1, wherein as seen in the axial direction, a rectangle circumscribing the flattened shape of the expansion part has a length in a longitudinal direction larger than a shortest distance between the two chamber sub-ports.

3. The scroll compressor of claim 1, wherein as seen in the axial direction, the main port lies on a central axis, the central axis being a central axis in a transverse direction of a rectangle circumscribing the flattened shape.

4. The scroll compressor of claim 1, wherein as seen in the axial direction, the discharge hole lies on a central axis, the central axis being a central axis in a transverse direction of a rectangle circumscribing the flattened shape.

5. The scroll compressor of claim 1, wherein as seen in the axial direction, the expansion part has a shape obtained by connecting outlines of a plurality of flattened shapes, the plurality of flattened shapes being positioned to partially overlap each other.

6. The scroll compressor of claim 1, wherein as seen in the axial direction, the expansion part has two parts including one part and an other part, the one part having a cross-sectional area greater than a cross-sectional area of the other part, the two parts are formed by dividing the expansion part by a central axis that is a central axis in a transverse direction of a rectangle circumscribing the flattened shape.

7. The scroll compressor of claim 1, wherein as seen in the axial direction, a longitudinal direction of a rectangle circumscribing the flattened shape of the expansion part, and a straight line connecting respective centers of the two chamber sub-ports form an angle θ , the angle θ satisfying a condition that $45^\circ \leq \theta \leq 135^\circ$.
